METHOD OF PRODUCING RIBOFLAVYL
PHOSPHATES

Leo A. Flexser, Upper Montclair, and Walter G. Farkas, Nutley, N. J., assignors to Hoffmann-La Roche Inc., Nutley, N. J., a corporation of New Jersey

11 Claims. (Cl. 260—211.3)

1

This invention relates to the manufacture of alkyl derivatives of riboflavin monophosphoric acid ester which is also designated as riboflavin phosphate or riboflavyl phosphate. More particularly, the invention is concerned with lower alkyl riboflavyl phosphates, i. e., mono- and di-lower alkyl riboflavyl phosphates, which are new and useful compounds. We have also found that by subjecting the lower alkyl riboflavyl phosphates to hydrolysis, hydrolysis occurs preferentially at the lower alkyl groups rather than at the riboflavyl group, and that substantially pure riboflavyl phosphate is produced. The new lower alkyl riboflavyl phosphates are, accordingly, useful for the preparation of riboflavin monophosphoric acid ester, which is a soluble form of vitamin B₂ and is of importance for its physiological activity. The mono lower alkyl riboflavyl phosphates hydrolyze with one molecule of water to give the corresponding lower alkanol and riboflavyl phosphate. In the case of the di-lower alkyl riboflavyl phosphates, two molecules of water are required for the hydrolysis. The hydrolysis is preferably carried out in the presence of a mineral acid, e. g., hydrochloric acid. Moderate warming facilitates the hydrolyzing action. By the hydrolysis, substantially pure riboflavin phosphate, free from lower alkyl phosphates and riboflavin, is readily prepared.

In general, the lower alkyl riboflavyl phosphates are prepared by reacting riboflavin with a lower alkyl chlorophosphoric acid ester, i. e., a mono lower alkyl dichlorophosphate or a di-lower alkyl monochlorophosphate. When a mono lower alkyl dichlorophosphate is employed in the reaction with riboflavin, there appears to be first produced an intermediate ester hydrochloride salt, namely, a mono lower alkyl riboflavyl chlorophosphate hydrochloride, which, after mild hydrolysis, yields a corresponding mono lower alkyl riboflavyl phosphate. When a di-lower alkyl monochlorophosphate is employed, there is probably first produced an intermediate ester hydrochloride salt, namely, a di-lower alkyl riboflavyl phosphate hydrochloride. The above is based on what we consider to be the most probable course of the reaction with the mono- and di-lower alkyl chlorophosphates, it being understood, however, that we do not wish to limit our invention to any specific theory of reaction.

As stated above, the mono- and di-lower alkyl riboflavyl phosphates can be further hydrolyzed to riboflavin phosphate. Such hydrolysis can

2

preferably be carried out in the presence of a mineral acid. Since the complete hydrolysis to riboflavin phosphate can be carried out directly on the reaction mixture of riboflavin and the lower alkyl chlorophosphates, it is not necessary to isolate the intermediate ester hydrochloride salts or the mono- or di-lower alkyl riboflavyl phosphates from the reaction mixture. In this case, the reaction mixture is sufficiently acid, so that further acid need not be added to facilitate the hydrolysis, the addition of water alone being sufficient to effect the hydrolysis.

In the preferred mode of practicing our process, we prepare the mono lower alkyl dichlorophosphate and the di-lower alkyl monochlorophosphate prior to reacting them with the riboflavin. This is done by reacting phosphorus oxychloride with about one to two moles of a lower alkanol, e. g., methanol or ethanol. When one mole of the lower alkanol is reacted with phosphorus oxychloride, the mono lower alkyl dichlorophosphate is obtained. When two moles of the lower alkanol are reacted with phosphorus oxychloride, the di-lower alkyl monochlorophosphate is obtained. These compounds need not be isolated from the reaction mixture, the riboflavin being merely added thereto for conversion to the corresponding lower alkyl riboflavyl phosphates.

Although it is preferred to prepare the lower alkyl chlorophosphates by prior reaction of phosphorus oxychloride with about one to two moles of the lower alkanol before addition of the riboflavin, it is to be understood that this order of addition of reactants is not critical. The preparation of the lower alkyl riboflavyl phosphates, may, for example, also be accomplished by admixture of the riboflavin and phosphorus oxychloride followed by careful addition of the lower alkanol. When the method is carried out in this way, practically no reaction occurs between the riboflavin and the phosphorus oxychloride alone. However, when the lower alkanol is added, hydrogen chloride is evolved and the lower alkyl chlorophosphate is formed which then reacts upon the riboflavin. This procedure is attended by the possibility that some destruction of riboflavin may occur as considerable heat is generated when the alkanol contacts and reacts with the phosphorus oxychloride. Accordingly, it is preferred to react the alkanol and phosphorus oxychloride before the addition of the riboflavin in order to eliminate the destruction of the latter by local overheating. If, in addition, several hours are allowed to elapse

before riboflavin is added, a better yield of the lower alkyl riboflavin phosphate is obtained, since the lower alkyl chlorophosphate will then be given sufficient time to be formed in optimal quantities for reaction.

The following examples will serve to illustrate the practice of our invention. It will be understood that the examples are illustrative only and are not intended to restrict the scope of the invention.

EXAMPLE I

Monomethyl riboflavin phosphate

To 36.6 cc. of phosphorus oxychloride (0.4 mole) were added slowly with stirring and cooling to room temperature 16.2 cc. of methanol (0.4 mole). After evolution of HCl gas had subsided, the reaction mixture, which contained monomethyl dichlorophosphate, was allowed to stand for about 16 hours. 3.76 grams of riboflavin (0.01 mole) were added. Rapid solution took place and the solution was stirred for 5 hours at room temperature. It was then poured with cooling to room temperature into 500 cc. of anhydrous ether. The resulting yellow precipitate of the intermediate ester salt (monomethyl riboflavin chlorophosphate hydrochloride) was filtered off, washed with ether and dried in vacuo. The dry substance was dissolved in a mixture of 36 cc. of dioxane and 4 cc. of water. Shortly after complete solution was obtained, crystallization of monomethyl riboflavin phosphate occurred. The product was filtered off, washed with dioxane and ether, and dried. On potentiometric titration with sodium hydroxide a single inflection point, occurring at pH 5.0, was found.

EXAMPLE II

Riboflavin monophosphoric acid ester

The monomethyl riboflavin phosphate obtained in Example I was dissolved in 5 cc. of concentrated (36 per cent) hydrochloric acid to which were subsequently added 30 cc. of water. A syrup thereupon precipitated which crystallized on stirring. The riboflavin monophosphoric acid ester thus obtained was filtered off, washed with ethanol, and dried.

EXAMPLE III

Dimethyl riboflavin phosphate

To 36.6 cc. of phosphorus oxychloride were added with cooling to room temperature and stirring 32.4 cc. of methanol (0.8 mole). After evolution of HCl gas had subsided, the reaction product, which contained dimethyl monochlorophosphate, was allowed to stand for about 16 hours. 3.76 grams of riboflavin were then added. Rapid solution took place, and the solution was stirred at room temperature for 6½ hours. It was then poured with cooling into 500 cc. of anhydrous ether. The intermediate ester salt (dimethyl riboflavin phosphate hydrochloride) separated as a syrup which was washed with ether. The syrup, upon treatment with ice, formed dimethyl riboflavin phosphate which crystallized. The resulting slurry was filtered, the crystals washed with water, alcohol and ether, and dried in vacuo. The dimethyl riboflavin phosphate thus obtained showed no acidic properties, being the neutral phosphate ester.

EXAMPLE IV

Riboflavin monophosphoric acid ester

0.5 gram of dimethyl riboflavin phosphate ob-

tained as in Example III was dissolved in one cc. of concentrated hydrochloric acid and the solution diluted with five volumes of water. The product which crystallized was riboflavin monophosphoric acid ester.

EXAMPLE V

Monoethyl riboflavin phosphate

- 10 To 36.6 cc. of phosphorus oxychloride were added slowly with stirring and cooling to room temperature 23.3 cc. of anhydrous ethanol (0.4 mole). After evolution of HCl gas had subsided, the reaction mixture, which contained monoethyl dichlorophosphate, was allowed to stand for about 16 hours. 3.76 grams of riboflavin were then added. Rapid solution occurred, and the resulting solution was stirred for 7½ hours at room temperature. It was then poured with cooling into 500 cc. of dry ether. The resulting precipitate of intermediate ester salt (monoethyl riboflavin chlorophosphate hydrochloride) was filtered, washed with ether, and dried in vacuo. The dried substance was dissolved in a mixture of 36 cc. of dioxane and 4 cc. of water. After 20 minutes, crystallization of monoethyl riboflavin phosphate occurred. The product was filtered off, washed with dioxane and ether, and dried. Potentiometric titration with sodium hydroxide showed a single inflection point at about pH 5.

EXAMPLE VI

Diethyl riboflavin phosphate

- 35 To 36.6 cc. of phosphorus oxychloride were added slowly and with stirring 46.6 cc. (0.8 mole) of anhydrous ethanol while maintaining the temperature at 20-25° C. After evolution of HCl gas had subsided, the reaction mixture, which contained diethyl monochlorophosphate, was permitted to stand for about 16 hours. 3.76 grams of riboflavin were then added and the resulting mixture was stirred and warmed to 50° C., after which solution occurred in about 10 minutes. The resulting solution was cooled to room temperature and maintained at that temperature for 3 hours. 500 cc. of anhydrous ether were then added. The resulting precipitate of the intermediate ester salt (diethyl riboflavin phosphate hydrochloride) was filtered off, washed with ether and dried. The substance was treated with 50 grams of an ice-water mixture, whereupon diethyl riboflavin phosphate was formed, which was separated by centrifugation, washed with alcohol and dried.

EXAMPLE VII

- 60 To 36.6 cc. of phosphorus oxychloride were added slowly and with stirring 46.6 cc. of anhydrous ethanol while maintaining the temperature at 20-25° C. After evolution of HCl gas had subsided, the reaction mixture, which contained diethyl monochlorophosphate, was permitted to stand for about 16 hours. 3.76 grams of riboflavin were then added and the resulting mixture was stirred and warmed to 50° C. for 4 hours. It was then cooled and the clear solution was added to 600 cc. of anhydrous ether. The resulting intermediate ester salt (diethyl riboflavin phosphate hydrochloride) separated out as a gummy material and was washed with ether. The substance was then added to 50 cc. of water, whereupon solution occurred accompanied by a slight rise in temperature. Upon 75 cooling, riboflavin phosphate crystallized there-

from, and was filtered, washed with 1 N HCl, ethanol and ether, and dried.

The following example will serve to illustrate the direct preparation of riboflavin phosphate without isolation of the intermediate ester salts or the lower alkyl riboflavin phosphates:

EXAMPLE VIII

To 73.2 cc. of phosphorus oxychloride (0.8 mole) were added with cooling to room temperature and stirring 64.8 cc. of methanol (1.6 moles). After evolution of HCl gas had subsided, the reaction product, which contained dimethyl monochlorophosphate, was allowed to stand for about 16 hours. 15.04 grams (0.04 mole) of riboflavin were then added. Solution took place in about 5 minutes. The resulting solution was stirred for 8 hours at room temperature. Then 50 cc. of water were slowly added, the temperature rising to 85° C. after which 100 cc. more of water were added. Crystallization of riboflavin monophosphoric acid ester occurred rapidly and was allowed to continue for about 16 hours. The product was then filtered, washed with 1 N HCl, ethanol and ether, and dried. The product thus obtained was essentially pure riboflavin phosphate.

We claim:

1. A process for manufacturing lower alkyl riboflavin phosphates which comprises reacting riboflavin with a compound selected from the group consisting of a mono lower alkyl dichlorophosphate and a di- lower alkyl monochlorophosphate.
2. A process for manufacturing monomethyl riboflavin phosphate which comprises reacting riboflavin with monomethyl dichlorophosphate.
3. A process for manufacturing dimethyl riboflavin phosphate which comprises reacting riboflavin with dimethyl monochlorophosphate.
4. A process for manufacturing monoethyl riboflavin phosphate which comprises reacting riboflavin with monoethyl dichlorophosphate.
5. A process for manufacturing diethyl riboflavin phosphate which comprises reacting riboflavin with diethyl monochlorophosphate.

6. A process which comprises reacting riboflavin phosphate which comprises reacting ribo- a mono lower alkyl dichlorophosphate and a di- lower alkyl monochlorophosphate and hydrolyzing the resulting reaction product so as to produce riboflavin phosphate.

7. A process which comprises reacting riboflavin with dimethyl monochlorophosphate and hydrolyzing the resulting reaction product so as to produce riboflavin phosphate.

8. A process which comprises reacting riboflavin with monomethyl dichlorophosphate and hydrolyzing the resulting reaction product so as to produce riboflavin phosphate.

9. A process which comprises hydrolyzing a compound selected from the group consisting of mono- and di- lower alkyl riboflavin phosphates so as to produce riboflavin phosphate.

10. A process which comprises hydrolyzing monomethyl riboflavin phosphate so as to produce riboflavin phosphate.

11. A process which comprises hydrolyzing dimethyl riboflavin phosphate so as to produce riboflavin phosphate.
